TRANSPARENT AWNING

Arthur Olsen, Rosedale, N. Y.

Application September 3, 1952, Serial No. 307,641

1 Claim. (Cl. 20—57.5)

This invention relates to awnings particularly of the type having permanently mounted frames, and in particular an awning having glass panels, or panels of other transparent material mounted in frames extended from a window frame whereby the transparent panels may be removed and replaced with panels of tinted or slightly colored material to eliminate glare rays.

The purpose of this invention is to provide an awning that makes it possible to open a window without rain passing through the window and without obstructing the passage of light through the window.

Various types of awnings have been used and awnings with adjustable slats have been provided to permit passage of light without permitting rain to enter the window. However, whereas such devices are satisfactory for average use they do not provide a full light opening and they do not prevent passage of rain where the rain is driven by a high wind. With this thought in mind this invention contemplates a box like structure having panels of transparent material mounted in comparatively thin frames whereby the passage of light is not obstructed and wherein the passage of rain through the window is definitely prevented.

The object of this invention is, therefore, to provide means for forming an awning whereby a window may be open in a heavy rain and wherein light passing through the window is not obstructed.

Another object of the invention is to provide a transparent awning that may be raised or lowered to compensate for the position of the window sash.

Another important object of the invention is to provide a transparent awning that is adapted to be used in combination with casement windows.

A further object of the invention is to provide a transparent awning which is of a simple and economical construction.

With these and other objects and advantages in view the invention embodies spaced triangularly shaped frames connected by cross members with panels of transparent material positioned in the frames and the frames may be mounted directly on the window frame or held in channels to facilitate adjusting the elevation of the awning.

Other features and advantages of the invention will appear from the following description taken in connection with the drawings, wherein:

Figure 1 is an elevational view showing a transparent awning mounted on a window frame.

Figure 2 is a cross section through the awning taken on line 2—2 of Figure 1 and showing the parts on an enlarged scale.

Figure 3 is a section similar to that shown in Figure 2 taken on line 3—3 of Figure 1, showing an intermediate support for reinforcing the transparent panel between the end frames of the awning.

Figure 4 is a detail showing a section similar to that shown in Figures 1, 2 and 3 on a further enlarged scale and illustrating the mounting at the upper edge of the awning.

Figure 5 is a sectional plan taken on line 5—5 of Figure 2 illustrating the method of attaching the vertical

2

members of the end frames of the awning to a window frame.

Figure 6 is a cross section taken on line 6—6 of Figure 2 showing the method of retaining the transparent panels in the corner rails.

Figure 7 is a section taken on line 7—7 of Figure 2 showing clips for holding the triangular shaped panels in the vertical rails of the frames.

Figure 8 is a section through the upper sloping surface of the awning taken on line 8—8 of Figure 1 also with the parts shown on an enlarged scale and showing the corner rails and also an intermediate support.

Figure 9 is a detail illustrating a corner section of a U-shape binding channel extended around the edges of the panels.

Figure 10 is a cross section through the channel shown in Figure 9 being taken on line 10—10 thereof.

Figure 11 is a front elevational view of the transparent awning illustrating a modification wherein the awning frame is adjustably mounted on a window frame.

Figure 12 is an end elevational view of the awning shown in Figure 11.

Figure 13 is a detail on an enlarged scale showing a section through the vertical rail of the awning frame said section being taken on line 13—13 of Figure 11.

Figure 14 is a view illustrating a further modification wherein a box like awning is provided for casement windows.

Figure 15 is a detail taken on line 15—15 of Figure 14 showing the upper corner rail of the awning shown in Figure 14.

Figure 16 is a cross section similar to that shown in Figures 2 and 3 on a reduced scale showing means for connecting horizontal rails to the triangularly shaped end frames of the awning.

Figure 17 is a top plan view of the awning frame taken on line 17—17 of Figure 16.

Figure 18 is a detail showing a section through the corner rail of the awning shown in Figures 16 and 17.

Figure 19 is a vertical section through one of the vertical side rails showing the meeting surfaces of the frame and rail corrugated.

Figure 20 is a section similar to that shown in Fig. 13 with the parts reversed wherein a channel section slides over a supporting rail.

Referring now to the drawings wherein like reference characters denote corresponding parts the improved transparent awning of this invention includes a panel 10 of transparent material, triangular shaped panels 11 and 12 also of transparent material, triangular shaped end frames having vertical rails 13, horizontal rails 14 and inclined rails 15 at one end and similar frames having vertical rails 16, horizontal rails 17 and inclined rails 18, at the opposite end with a lower bar 19 connecting the lower corners of the frames and an upper bar 20 connecting the upper corners of the frames and having a protecting baffle 21 on the outer surface under which the upper edge of the panel 10 is positioned, as shown in Fig. 4.

The edges of the panels 10, 11 and 12 are protected with continuous binding channels, as indicated by the numeral 22, the channels being U-shaped in cross section with flanges 23 and 24 extended from the edges of the backs or webs, to which the numeral 22 refers, and the flange on one side is provided with clips 25 the outer edges of which are formed with projections or lips 26.

The vertically disposed rails 13 and 16 of the end frames are formed as illustrated in Figs. 5 and 7 with recesses 27 in which the binding channels on the edges of the panels 11 and 12 are positioned and the rails are also provided with notches 28 that are positioned to receive the lips 26 of the flanges or clips 25.

By this means the transparent panels, which may be

formed of glass, plastic or other suitable material may be positioned in the recesses of the rails with the clips 25 sprung to permit the lips 26 to slide over the surfaces of the rails and as the panels are positioned in the recesses the lips 26 snap into the grooves or notches 28. With the panels held in position in this manner it is only necessary to pry the clips 25 outwardly with a screwdriver or the like whereby the lips 26 are drawn from the notches and the panels or frames are free so that they may readily be removed and replaced.

As illustrated in Figure 5, the vertical rails 13 and 16 are provided with mounting flanges 29 which are secured to the rails with screws 30 and the flanges are secured to the sides of a window frame, as indicated by the numeral 31 by fasteners 32. The upper ends of the vertically disposed rails are connected with the cross plates 20 and the member 21 is mounted on the cross plates. With the parts formed in this manner the upper transparent panel 10 extends in under the member 21 thereby providing a seal at the upper edge of the frame.

As illustrated in Figures 6 and 8 the upper corner rails 15 and 18 of the frame are provided with recesses in which edges of the panels are positioned and notches 33 are provided in the inner surfaces to receive the lips 26 of the clips 25.

The rail 18 is provided with a recess 34 in which one edge of the panel 10 is positioned and a similar recess 35 is provided in the rail 15 to receive the opposite end of the panel 10. The rail 18 is also provided with a recess 36 which receives the upper edge of the end panel 11 and a similar recess 37 is provided in the rail 15 for receiving the upper edge of the end panel 12. The panel 10 is also supported to the center with a bar or support member 38, the upper end of which is secured to the cross plate 20, and the lower end to the cross bar 19 which forms a lower outer edge of the awning. The clips 25 with the lips 26 are provided at different points in the frames.

As illustrated in Figures 16, 17 and 18 end frames similar to the frames formed with the rails 13, 14 and 15 at one end and 16, 17 and 18 at the other, may be connected with cross bars, with a bar 40 at the lower edge, similar to the bar 19 and a bar 41 at the upper edge, similar to the plate 20. In this design the end frames as indicated by the numerals 42 and 43 are secured to the ends of the cross bars with screws 44 and an intermediate support bar 45 is secured to the rails or bars 40 and 41 with screws 46. The end frames and also the section for receiving the panel 10 are otherwise similar to the end frame shown in Figures 1, 2 and 3, the rails and bars of the frames being provided with recesses shown in Figures 6, 7 and 8 whereby the same transparent panels are adapted to be used in both types of awning.

In the design illustrated in Figures 11, 12 and 13 a transparent panel 50, similar to the panel 10 is supported with end frames 51 and 52 with the lower outer corners connected with a cross bar 53 and with the upper ends positioned below a member 54, similar to the member 21.

In this design vertical rails 55 of the end frames are secured to bars 56 with screws 57 and the bars 56 are slidably mounted in channels 58 which are formed with arcuate flanges at the edges in which arcuate ends of the bars 56 are nested. The bar 56 is also provided with a thumb screw 59 to facilitate clamping the frames of the awning in adjusted position.

With the parts arranged in this manner channels 58 are positioned on the outer surface of a window frame, as shown in Figures 11 and 12 and the position of the awning is vertically adjustable to compensate for the position of the screen or opening through a window on which the awning is mounted. With the upper sash of a window lowered the awning is positioned at the top of the window and with the lower sash raised the awning may be dropped downwardly to cover the opening between the lower edge of the lower sash and window sill. 75

In the design illustrated in Figures 14 and 15 the upper end of the awning is extended outwardly to permit casement sash 60 of a window having a frame 61 with a sill 62 to open outwardly, and in this design the owning is provided with a front panel 63, end panel 64 and a top panel 65. At the upper outer corner of the awning a cross rail 66 is provided in which recesses 67 and 68 receive edges of the transparent panels 65 and 63, respectively.

10 The end panels 64 are positioned in end frames having vertical rails 69, upper horizontal rails 70, lower horizontal rails 71 and outer inclined rails 72, and the vertical rails 69 are provided with flanges 73 by which the end frames are secured to the window frame. A cross member 74 is also provided to extend across the upper edge of the top panel 65, similar to the member 21, shown in Figure 4.

15 In the design shown in Figure 20 the parts are reversed as compared with the mounting shown in Fig. 13, a channel shaped member 75, similar to the member 58 being secured to a rail 76, similar to the rail 55, and the member 75 is slidably mounted on a rail 77 on a window frame 78. The member 75 is provided with a thumb screw 79 for clamping the parts in adjusted positions and 25 the member 75 is secured to the rail 76 with screws or the like.

20 In the modification illustrated in Fig. 19 the channel member 80 similar to the member 58 is provided with horizontally disposed corrugations 81 and similar corrugations 82 are provided in the rail 83, similar to the rail 56. The corrugations, in combination with the thumb screw 84 provide means for positively locking the parts in adjusted positions.

25 The transparent awning of this invention may, therefore, be provided in different forms, however, in each design transparent panels are positioned with edges thereof in recesses of vertical, horizontal, and inclined rails or bars and frames in which the rails and bars are included are permanently or adjustably attached to the outer face of a window frame, as may be desired.

30 It will be understood that other modifications, within the scope of the appended claim, may be made in the design and arrangement of the parts without departing from the spirit of the invention.

35 45 What is claimed is:

In a transparent awning, an inclined panel of transparent material, a pair of spaced, parallel vertically disposed triangular shaped panels also of transparent material, triangular shaped end frames each including vertical rails, horizontal rails and inclined rails, upper and lower spaced, parallel bars interconnecting the corners of said frames together, a baffle arranged contiguous to said upper bar and extending over the upper end of said inclined panel, U-shaped channels arranged in engagement with the edges of said panels and provided with clips having lips extending therefrom, there being recesses in certain of said rails for receiving said channels, there being notches in certain of said rails for at times receiving said lips, said lips adapted to selectively slide over the surfaces of said rails, flanges secured to said vertical rails and adapted to be secured to the sides of a window frame, said inclined rails being provided with recesses for receiving the edges of said triangular panels, and an inclined support member extending below said inclined bars and having its ends secured to said upper and lower bars.
